UNITED STATES PATENT OFFICE.

MERRITT P. WHEELER, OF PAWHUSKA, OKLAHOMA.

RAIL-FASTENER.

1,163,728.

Specification of Letters Patent.

Patented Dec. 14, 1915.

Application filed July 18, 1913. Serial No. 779,707.

To all whom it may concern:

Be it known that I, MERRITT P. WHEELER, a citizen of the United States, residing at Pawhuska, in the county of Osage and State 5 of Oklahoma, have invented certain new and useful Improvements in Rail-Fasteners, of which the following is a specification.

This invention relates to rail joints and has for its primary object to provide a novel 10 form of locking means for retaining the meeting ends of a rail in engagement, thereby preventing many accidents which have heretofore occurred due to inefficient rail joints.

Another object of the invention is to provide splice bars of the ordinary type, which are in engagement with the web of the rail, the splice bars being connected to the rail through the medium of a suitable detachable 20 element, the element being held from displacement due to the vibration of the rolling stock passing over the rail, in a simple and efficient manner which will be more fully hereinafter set forth.

Other objects as well as the nature, characteristic features and scope of the invention will be more readily understood from the following description taken in connection with the accompanying drawings and pointed 25 out in the claims forming a part of this specification.

Referring to the drawings—Figure 1 is a side elevation of a rail illustrating the application of my invention; Fig. 2 is a cross 35 sectional view taken on the line 2—2 of Fig. 1; Fig. 3 is a detail fragmentary elevation of one of the splice bars; and Fig. 4 is a detail enlarged cross sectional view of the locking means taken on the line 4—4 of 40 Fig. 2.

In the drawings wherein is illustrated the preferred form of the present invention a rail is provided which comprises a base flange 5, a web 6 and a head 7, which may 45 be of the ordinary or any desired form. Arranged between the head 7 and the base flange 5 are splice bars or fish plates 8, one of which is arranged on each side of the web 6, and engaged therewith. The web 6 and 50 the fish plates 8, are provided with a plurality of alining apertures 9 which are arranged at intervals therein, and are screw-threaded for engagement with the locking element.

The locking element in the present instance comprises a bolt having an elongated

externally screw-threaded shank 10 and an enlarged substantially rectangular head 11, the head 11 being provided in each of the sides thereof with a semi-circular recess 12 60 which is engaged by the shank 13 of the auxiliary locking element 14. The auxiliary locking element comprises a shank 13 above mentioned the one end of which is screw-threaded as indicated at 15, the opposite 65 end thereof being provided with a head 16 which has formed therein a transversely extending groove 17. The screw-threaded end 15 of the auxiliary locking element 14, is adapted for screw-threaded engagement in 70 an aperture 18 which is provided adjacent the apertures 9 in one of the fish plates, either at the side thereof or subjacent the same as desired.

In operation, after the meeting ends of the 75 rail 7, have been placed together, the fish plates or splice bars 8 are placed in engagement with the web 6 of the rail in the ordinary manner, having the apertures of the fish plates alining with the apertures of the 80 web. The locking element has the shank 10 thereof threaded through the apertures 9 until the inner face of the head 11 thereof contacts with the outer face of one of the fish plates 8. The auxiliary element 14 has 85 the threaded shank 15 thereof engaged in the aperture 18, the smooth portion 13 of the shank being in engagement with one of the semi-circular recesses 12 of the head 11. The auxiliary element 14 is rotated, through 90 the medium of a screw-driver or a similar tool, which is engaged in the transversely extending groove 17, until the inner face of the head 16 engages with the outer end of the head 11. When in this position it is obvious that the rotation of the locking element proper is prevented, not only by having the sides of the head 11 engaging with the shank 13 of the auxiliary element but it 95 will also be assisted in its locking function in view of the fact that when the auxiliary element 14 is in its position, adjacent the aperture 9 of one of the fish plates, the threads on the shank of the locking element proper will be caused to bind in said apertures 9, 100 thereby facilitating the retaining of the locking element proper in the apertures 9, 105 so as to prevent the displacement of the meeting ends of the rail.

It will be understood that the above de- 110 scription and accompanying drawings comprehend only the general and preferred

embodiment of my invention and that various minor changes in details of construction, proportion and arrangement of the parts may be made within the scope of the appended claim and without sacrificing any of the advantages of my invention.

Having thus fully described my invention what I claim as new and desire to secure by Letters Patent is:—

10 The combination with a pair of rails and fish-plates having registering openings therein, and a screw threaded opening in the fish-plates adjacent to the registering openings, of a bolt having an enlarged

head, semi-circular recesses in opposite sides 15 of the head, said bolt passing through the registering openings, an auxiliary bolt engaging with the screw threaded opening in the fish-plate, and resting in the recesses in the main bolt, the head of the auxiliary 20 bolt overlying the head of the main bolt.

In testimony whereof I affix my signature in presence of two witnesses.

MERRITT P. WHEELER.
